UNITED STATES PATENT OFFICE

ALEXANDER BELDIMANO, OF ROTTERDAM, NETHERLANDS

CONTAINER FOR GASES OR LIQUIDS UNDER HIGH PRESSURE

Application filed June 18, 1929, Serial No. 371,948, and in Germany June 26, 1928.

This invention relates to containers for gases or liquids under high pressure. In order that containers of this type are capable to resist to the high internal pressure, they 5 have been constructed hitherto in cylindrical shape and with a correspondingly thick wall. Now the size that can be given to such containers is a very limited one, because in a container of comparatively great diameter and 10 intended to resist to a high specific gas pressure, for instance about 200 atm., this pressure becomes so high that excessively great wall thickness is needed to resist to it. Such containers therefore would be not only too expensive, but when having a correspondingly 15 great diameter, their manufacture would be impossible at all.

Now the object of the invention is to afford big containers for gases and liquids under 20 high pressure and having comparatively thin walls which object is obtained by providing double walls and filling the space existing between them with a means impervious to fluids while the walls are propped relatively 25 to one another.

When the container has a quadrangular cross section, the propping means may consist of anchor bolts extending normally to the walls, whilst in a cylindrical container 30 the walls may be propped by supporting members which extend annularly or spirally inside or outside the outer wall.

In order that the invention can be more readily understood, some embodiments of the 35 same are illustrated by way of example in the accompanying drawings.

Fig. 1 is a longitudinal sectional view of one form of my invention,

Figs. 2-4 are longitudinal sectional views 40 of different embodiments thereof.

In the embodiments illustrated in Figures 1 to 3 the container consists of a jacket *a* and a container proper *b* of any suitable material such as metal, concrete or the like, the space 45 *c* existing between jacket *a* and container *b* being filled with a viscous liquid impervious to fluids for instance of a nature so as to be thick or solid at normal temperature but when heated becomes liquid and then is capable to fill the entire intermediate space *c*.

Tar or a similar material may be used for this purpose.

The container *b* may have only a comparatively small wall thickness as it transmits the internal pressure through the tightening 55 mass *e* to the jacket *a* which is anchored in itself. The concrete wall of the latter can be made of armored concrete.

In order to mutually prop the outer walls of the described gas or liquid container of 60 quadrangular cross section, anchor bolts *d*, *e*, *f*, Figure 1, are provided which as to be seen from this figure either pass through the wall of the jacket *a* and are held in place by nuts *g* and washers *m* of suitable size, or have 65 their ends embedded in the wall of jacket *a* as illustrated in Figure 2, which ends have any suitable shape so as to reliably anchor the bolts within the wall of jacket *a*.

As to be seen from Figure 4, the longitudinal anchor bolts *e* of Figures 1 to 3 may be dispensed with in an oblong container as illustrated, by designing the front walls of the jacket *a* so as to subside into abutments *h* which have a correspondingly large base 70 *i* the area of which must correspond to the internal pressure acting on the front walls. As containers of this type generally are embedded in the ground the earth mass in its turn forms the abutment for the abutments *h*. 75

As illustrated in Figures 2 and 3, iron rods *k* may be further provided which are embedded or inserted in the wall of jacket *a*. The modification illustrated in Figure 3 may also be used in erecting cylindrical containers. 80

In the embodiment illustrated in Figure 4 the front walls of jacket *a* are likewise propped on one another by longitudinal anchor bolts *e* whilst the side wall, if cylindrical, is so strengthened either by external metal rings or by a coiled wire *n* so as to resist to radial pressure. 85

The described containers are kept tight by the above mentioned viscous substance without pores, as marked by *c*, whilst the internal pressure is transmitted to the anchor bolts that prop the walls, or to outer abutments *h* on which the walls rest. 95

It is, of course, to be understood that the 100

invention is not limited to the embodiments herein described, but is susceptible of embodiment in various forms without deviating from the essence of the invention.

5 All described containers are absolutely tight even when exposed to the highest pressures, and can have any great dimensions, while the manufacturing costs are very low.

Claims:

- 10 1. A container for gases or liquids under high pressure, comprising an inner and an outer container spaced from each other, a viscous substance impervious to fluids in the space between said containers, means for 15 bracing said outer container to withstand pressure, said inner container serving merely as a partition between the contents of said inner container and said viscous substance.
- 20 2. A container as specified in claim 1, adapted to be embedded in the ground, said outer container comprising end walls and side walls, said bracing means comprising foundation members having large base surfaces, said end walls abutting on said end 25 members and means for bracing said side walls.
- 30 3. A container as specified in claim 1 in which said outer container is of cylindrical shape, said outer container comprising end walls and cylindrical side walls, and said bracing means comprising tie rods extending longitudinally of said container and mutually bracing said end walls, bracing means encircling said side walls.
- 35 4. A container as specified in claim 1 in which said outer container comprises end walls and side walls, and said bracing means comprises said tie rods extending longitudinally of said container and mutually bracing 40 said end walls, and tie rods extending transversely of said container and mutually bracing said side walls.

The foregoing specification signed at Rotterdam, Netherlands, this fifth day of June, 45 1929.

ALEXANDER BELDIMANO.
